(57) **CLAIM**

The ornamental design for a display screen or portion thereof with icon, as shown and described herein.

DESCRIPTION

FIG. 1 is a front view of the display screen or portion thereof with icon, the icon is shown separately for clarity of illustration, and on an enlarged scale; and,

FIG. 2 is a front view of a display screen or portion thereof with icon, showing our new design.

The dash-dot broken lines shown in FIGS. 1 and 2 represent an unclaimed boundary line and form no part of the claimed design.

The dash-dash broken lines shown in FIG. 2 depict the display screen or portion thereof and form no part of the claimed design.

1 Claim, 2 Drawing Sheets
